(57) **CLAIM**

The ornamental design for a potty chair, as shown and described.

DESCRIPTION

FIG. 1 is a perspective view of the potty chair;

FIG. 2 is a top view of the potty chair;

FIG. 3 is a front view of the potty chair;

FIG. 4 is a left side view of the potty chair;

FIG. 5 is a bottom view of the potty chair;

FIG. 6 is a rear view of the potty chair; and,

FIG. 7 is a right side view of the potty chair.

The broken lines in the figures showing portions of the potty chair in FIGS. 1-7 are for illustrative purposes only and form no part of the claimed design.
